ATTORNEY

UNITED STATES PATENT OFFICE

WILLIAM A. DIXON, OF TAFT, OREGON, ASSIGNOR TO LINCOLN COUNTY LOGGING COMPANY, OF TAFT, OREGON

LOG RAFT

Application filed March 29, 1928. Serial No. 265,552.

This invention relates generally to the transportation of logs by means of rafts, with special reference to rafts which are adapted to use in shallow waters as well as in deeper waters or in the ocean itself.

The main object of this invention is to construct a form of log raft which will make it possible to build and to float the raft in relatively shallow waters, and at the same time make same seagoing, without the necessity of expending an undesirable amount of labor in its construction or entailing the loss of a large percentage of the logs, as is ordinarily the case when they are drilled at each end for the purpose of fastening them together by means of cables.

These objects will become more apparent from the specification following as illustrated in the accompanying drawings, in which:

20 Figure 1 is a perspective view of the raft showing same being towed by a power vessel. Figure 2 is a plan of a completed raft. Figure 3 is a plan of the lower tier of logs showing the single cross log at the stern of the raft. Figure 4 is an enlarged section taken along the line 4—4 in Figure 2 showing the lower tier of logs and cable. Figure 5 is a section taken along the line 5—5 in Figure 2 showing the raft after the second tier of logs is piled thereon. Figure 6 is a section taken along the line 6—6 in Figure 2. Figure 7 is a vertical section taken along the line 7—7 in Figure 5 showing the cross log at the stern of the raft and its fastening to the lower tier of logs.

Similar numbers of reference refer to similar parts throughout the several views.

Referring in detail to the drawing, the raft is constructed as follows: First there are floated into position a number of long outer logs 10, preferably over-lapping (as shown), and between which are placed the shorter logs 11 which are also over-lapped as much as possible. It is desirable to use logs of a fairly uniform size for the lower tier.

The logs 10 and 11 are now secured together at intervals by means of a cable 12 which is wound up and down around the logs in figure eight fashion (as shown in Figure 4) and the lashings are pulled up as tight

as possible, after which it is made fast by the clamps 13.

Next a cross log 14 is placed across the stern of the raft and is made fast thereto by means of the cable 15 (as shown). The log 14 is 55 provided with notches 16 on its upper side to prevent the cable from slipping. The cable 15 is then secured by means of the clamps 17.

The portion of the raft thus far described 60 provides the required buoyancy and the cross log 14 holds the stern to a flat bottom and provides a stop for the cargo, which consists of a second tier of logs 18 which may be of any size or length, although it is also preferable to over-lap these logs as well as those in the lower tier.

The logs 18 are now held down by the cross logs 19 and 20 and positioned approximately as shown in the drawing, and made fast by the cables 21 which pass over the cross logs 19 and 20 and under the logs 10 and 11, in other words, binding the cargo logs to the raft logs, and at the same time holding the under side of the raft to a flat bottom, which 70 of course is desirable when rafting logs in shallow waters. The hauling lines 22 are made fast to the log 14 and then given a turn around the cross logs 19 and 20 and then attached to the bridle 23, to which is secured 75 the tow line 24 of the power boat 25.

It can be seen that by this construction the logs 10 and 11 in the lower tier not only support the cargo logs 18 but are more rigidly held in their relation to each other by the 80 cargo logs 18. In other words, after the cable 12 is wrapped up and down through the logs 10 and 11 and drawn as tightly as possible and secured by the clamps 13 there 85 may still be considerable slack in the cable owing to the stiffness of the cable itself. This is taken care of by the cargo logs themselves which tend to spread the lower logs apart so that as the cargo logs 18 are added to the raft it is gradually transformed into a 90 well knit structure capable of withstanding even rough sea travel.

It must be borne in mind that this raft is especially designed for rafting large logs such as are commonly found in the western 100

part of the United States where logs ranging from three to four feet in diameter are an average rather than an exception. This type of raft would probably not be advisable with the smaller logs found in the eastern and southern sections of the country.

It has been the common practice in rafting these large logs in shallow waters to bore a three inch hole through both ends of the logs about two feet from the end, threading steel cables through these holes by means of which the logs are secured together. While this method is fairly safe, it is extremely expensive as far as labor is concerned, and wasteful as far as timber is concerned, since it can readily be appreciated that two feet off of each end of each log of the diameters suggested would amount to a considerable amount of waste.

I am aware that many forms of log rafts have been constructed in the past; it is therefore not my intention to cover such devices broadly, but I do intend to cover all such forms and modifications thereof as fall fairly within the appended claims.

I claim:

1. A log raft consisting of a tier of longitudinally disposed logs having interlaced cable means for securing same together laterally, a cross log mounted on top of the stern end only of the raft formed by said longitudinally disposed logs and lashed thereto in a manner to hold the stern of said raft to a flat bottom, cargo logs placed on top of and between said lower logs, binding cross logs placed on top of said cargo logs having means for lashing same to the under side of said lower logs, and hauling lines secured to said stern cross log then passing around each of said binding logs and fastening to the bridle of a towing boat.

2. A log raft consisting of a plurality of longitudinally disposed logs, a cargo abutting cross log mounted at the stern end only of said first mentioned logs transversely therewith and projecting over the sides thereof, said cargo abutting log having notches formed in the top sides of its projecting ends, a cable passing around the under side of said longitudinal logs and said notched ends and secured thereto in a manner to hold said longitudinal logs in a horizontal plane, a plurality of transverse cables passed around said longitudinal logs for securing same together laterally, cargo logs above and between said longitudinally disposed logs, binding cross logs above said cargo logs urging said lowermost logs apart, cables for lashing said binding logs upon said cargo logs and passing under the lowermost logs, and hauling lines for securing said raft longitudinally and towing same consisting of a pair of lines made fast to opposite ends of said stern cross log then turned around said binding logs and then made fast to a towing bridle.

3. A method of building log rafts consisting of first placing a tier of logs in the water, then lashing said logs together laterally, then mounting a cargo abutting log across the top of the stern end of said logs, then placing a tier of cargo logs above and between said first mentioned logs with their rearmost ends against said stern logs, then binding said cargo logs against said first mentioned logs by means of a plurality of cross logs placed on top of said cargo logs and lashing around both tiers of logs, and then joining all of said logs longitudinally by means of tow lines secured to said stern and cross logs.
